UNITED STATES PATENT OFFICE.

JOSEPH B. ZIMMERS, OF CHICAGO, ILLINOIS.

UPHOLSTERY FINISH.

Application filed December 2, 1921. Serial No. 519,406.

To all whom it may concern:

Be it known that I, JOSEPH B. ZIMMERS, a citizen of the United States, residing at Chicago, in the county of Cook and State 5 of Illinois, have invented a new and useful Improvement in Upholstery Finish, of which the following is a specification.

My present invention pertains to finishing devices for upholstery, and more specifically to the edging of upholstery on automobiles, and such like vehicles. One of the primary objects of my invention is an upholstery trim where a metal edging can be firmly attached to hold the upholstery, 10 be decorative, and at the same time receive and retain an insert of the upholstery material or other decorative material. Another principal object is a product which can be easily removed, altered and re-installed to 15 suit varied decorative requirements. Other objects will readily appear to the initiated.

This application is a modification of, and is based fundamentally upon, my former application, Serial Number 376,231, filed 20 April 24, 1920.

In the drawings:

Figure 1 is a broken section showing assemblage of parts.

Figure 2 is a cross section of Fig. 1 on 25 line 2-2 (enlarged).

Figure 3 is a detail of an insert.

Figure 4 is a detail of the channel strip;

Figure 5 is an inverted detail view of the insert shown in Fig. 3.

As illustrated, my invention consists of 30 a strip of manually pliant semi-soft metal having a base 1, longitudinal edges 2-2 inwardly turned at acute angles to base 1, and edges 3-3 inwardly turned upon the

40 respective edges 2, 2, substantially parallel to the same, producing resultant edges 4, 4, forming a channel 5, but these inwardly turned upstanding edges may be solid without departing from the spirit of my invention. These edges 4, 4, may bear to 45 each other a relative tension. The base 1 has an arched centre 6, formed longitudinally thereon, and has perforations 7 transversely through the arched portion 6 for

50 receiving an attaching means. The arch formation in base 1 subserves two purposes; one, the better adjustment as a finishing edge, and a greater pliability than a flat base—while retaining its integrity. I pro-

55 vide a removable strip of flexible upholstery material 8 in the nature of leather, cloth

or fabric enfolding an elastic insert 9, preferably a strip of rubber having a convex crown and a concave base. For the purpose of better holding upholstery material 8 to 60 insert 9, I use an adhesive, but I reserve the right to use any ordinary means of temporarily holding the upholstery material 8 until it is inserted in the metal strip.

It will be observed that the metal strip 65 primarily forms an attaching and decorative means in upholstering, and it also forms a channel for retaining a removable insert, which insert is capable of the widest range in the use of decorative edging. The 70 elastic insert centre makes the insert easily insertable and easily removed while holding the upholstery material firmly intact after it is inserted.

My illustration is only to be limited by the 75 scope of the claims, and what I desire to secure by Letters Patent and claim is:

1. In an article of manufacture, the combination of a pliant metal channel formed with inwardly turned longitudinal edges; 80 and a pliant member associated therewith consisting of an upholstery element enfolded an elastic element inserted through the said channel edges and retained in and by the channel area. 85

2. An article of manufacture consisting in combination of a pliant metal channel formed with inwardly turned edges longitudinally, and an arched base; and an upholstery material enfolded an elastic element 90 removably insertible in and retained by the coaction of said turned edges and the elastic element confined within said channel area.

3. In an upholstery finishing device, the 95 combination of a pliant metal strip having its longitudinal edges inwardly turned at an acute angle to the base forming a finishing device and a retaining channel; an element coacting with said channel and frictionally held in said channel, consisting of an elastic strip enfolded by an upholstery material. 100

4. The combination of a pliant, non-re-silient metal strip having its longitudinal 105 edges forming a channel; a removable insert elastically held in said channel, said insert consisting of a strip of upholstery material enfolded an elastic material.

5. The combination of a metal non-re-silient channel; an elastic removable insert 110 frictionally engaging the walls of said chan-

nel; said insert consisting of a strip of upholstery material enfolding an elastic material.

6. An article of manufacture consisting of an attachable semi-soft metal strip having its edges inwardly turned forming a retaining channel; an elastic insert held in by the walls of said channel coacting with the said insert, said insert consisting of an elastic member enfolded by an upholstery member; a longitudinally arched base to the metal strip.

7. A channel consisting of a metal, manually pliable, having its channel edges inwardly turned forming an enclosed channel area; an elastic strip elastically held in and coacting with said channel edges; said elastic strip consisting of a resilient member enfolded by a covering member.

8. A manually pliable metal channel having inwardly turned edges; an elastic member retained in the channel area by its own elastic properties; said elastic member being enfolded by a covering member of suitable material to harmonize with the decorative scheme of the upholstery.

9. In an upholstery finish the combination of an elongated inelastic, manually pliable metal strip, its form consisting of a base having the longitudinal edges upwardly flanged and inwardly turned, the said edges, with the base forming a substantially rigid uniform channel—the base of the channel having a greater width than the width between the edges; an elongated rubber member having a base and a substantially semi-circular crown, its said crown covered by an elongated strip of finishing material;

the rubber member and the finishing material coacting with the inwardly turned edges of the metal portion whereby the said rubber and finishing material may be pressed into the said channel and be automatically held therein and thereby; holes perforating the said metal base whereby the metal finish may be rigidly attached to a body prior to the insertion of the rubber finishing material combination and be hidden by said insert.

10. In an upholstery edging finish, the combination of an inelastic, manually pliable metal strip consisting of a base slightly arched whereby its longitudinal edges are brought into intimate contact with the object to which it may be attached, the longitudinal edges extending upwardly and inwardly forming with said base a channel section whose base is of greater width than its opening, the arched base slightly intruding into the enclosed channel area; a member consisting of an elastic portion covered longitudinally by a decorative finishing material, said elastic portion being substantially semi-spherical in cross section and capable of being pressed retainingly in the channel of the metallic member after the said metallic channel member is affixed to an object, and capable of being easily removed therefrom; attaching means distributed along the base and adapted to be hidden by the said elastic member.

Signed at Chicago, in the county of Cook, and State of Illinois, this 31st day of October, 1921.

JOSEPH B. ZIMMERS.
